CPC E03C 1/04; E03C 1/0401; E03C 1/0402;

FIG. 1 is a raised perspective view of an embodiment of a lavatory fixture;

FIG. 2 is a front view of the lavatory fixture of the embodiment as shown in FIG. 1;

FIG. 3 is a rear view of the lavatory fixture of the embodiment as shown in FIG. 1;

FIG. 4 is a right-side view of the lavatory fixture of the embodiment as shown in FIG. 1;

FIG. 5 is a left-side view of the lavatory fixture of the embodiment as shown in FIG. 1;

FIG. 6 is a top view of the lavatory fixture of the embodiment as shown in FIG. 1;

FIG. 7 is a bottom view of the lavatory fixture of the embodiment as shown in FIG. 1; and,

FIG. 8 is a side perspective view of the lavatory fixture as shown in FIG. 1.

Any broken lines represent environmental structure and form no part of the claimed design. Further, the broken away

(Continued)

lines shown in the figures represent a boundary of the claimed design and the portion between the broken away lines is not claimed.
